UNITED STATES PATENT OFFICE

WALTER S. FINNELL, OF ELKHART, INDIANA

DESIGN FOR A HOUSING FOR FLOOR-TREATING MACHINE

Application filed May 9, 1930. Serial No. 35,559. Term of patent 14 years.

To all whom it may concern:

Be it known that I, WALTER S. FINNELL, a citizen of the United States, residing at Elkhart, county of Elkhart, State of Indiana, have invented a new, original, and ornamental Design for Housing for Floor-Treating Machine, of which the following is a specification, reference being had to the accompanying drawing, forming a part thereof.

In the drawing, Fig. 1 is a top plan view

of a housing for floor treating machine, showing my new design;

Fig. 2 is a front elevational view of the housing shown in Fig. 1; and

Fig. 3 is a side elevational view of the housing shown in Figs. 1 and 2.

I claim:

The ornamental design for a housing for floor treating machine, as shown.

WALTER S. FINNELL.
